BY J. C. Higdon

ATTORNEY.

UNITED STATES PATENT OFFICE.

ABIATHER CHADWICK, OF KANSAS CITY, MISSOURI.

REVERSIBLE COAL-CHUTE.

SPECIFICATION forming part of Letters Patent No. 313,471, dated March 10, 1885.

Application filed December 2, 1884. (No model.)

To all whom it may concern:

Be it known that I, ABIATHER CHADWICK, of Kansas City, Jackson county, Missouri, have invented a new and Improved Reversible Coal-Chute, of which the following is a full, clear, and exact description.

My invention has for its object the provision of improved means whereby box and stock cars may be readily loaded with coal or to the like without the intervention of hand-shoveling; and it consists, principally, in applying to the delivery or lower end of a chute a shunting-apron that is provided with a sliding hinge and is capable of being reversed or swung around in a horizontal plane, for the purpose of guiding the descending current of coal toward either end of the car, as may be desired.

Reference is to be had to the accompanying drawings, forming part of this specification, in which similar letters of reference indicate corresponding parts in each figure.

Figure 1 is a perspective view of the lower extremity of a chute having my improved apron applied thereto. Fig. 2 is a detail view in perspective of the locking-pin and its key. Fig. 3 is a plan view showing the underside of the apparatus. Fig. 4 is a section through the longitudinal line *g g*, Fig. 3. Fig. 5 is a plan view showing the upper side of the device, and Fig. 6 is a like view and exhibits the position of the apron when the apparatus is applied to a car-door.

My improved apron A, as shown in the plan views, is constructed of any approved material, in the form of a quarter-circle, and it is connected near its radius-point, by means of the hinge-piece *d*, to a rod, E, extending laterally from the sides K of the chute, beneath the bottom thereof, F. The said hinge-piece *d* is pivotally attached to the under side of the apron by means of the rivet or bolt *f*. The apron A is provided upon its circumference with a raised flange, B, corresponding in height to the chute-sides K. The flange is provided upon its upper edge with a raised portion, *b*, in order that a supporting-chain, H, (the lower extremity of which is adjustably connected thereto through the aperture *a*,) may not come in contact with the chute-sides.

The upper end of the said chain is attached centrally to the cross-bar *L'* of the supporting-frame L, and its lower end carries a hook, *h*, which may engage any desired link of the chain for the purpose of adjusting the apron in relation to the bottom of the chute. When the apron A is in the position shown in Fig. 1, the current of the coal descending the chute will come in contact with the flange B and be thrown toward one end of the car C; and when it is desired to fill the opposite end the fastening-bolt T (which passes through an aperture, D, in the outer corners of the flange B and through a corresponding aperture, *D'*, in the sides of the chute) is withdrawn by removing its key *t* from the aperture *e* in the said bolt. Then the apron A is swung around (the hinge *d* sliding upon the rod E) to a reverse position, as shown in Fig. 5.

I do not desire to limit myself to the fastening-bolt that I have shown, for it is obvious that a spring-latch could be substituted therefor.

When the apron is not in use, it may be swung inwardly from either side toward the screen S, as shown by the dotted lines B'. The edges R of the apron are turned slightly downward in order not to intercept the passage of the coal.

My improved shunting-apron may be termed an "open" apron, for the reason that it is not in tubular form and is devoid of any covering.

I am aware in loading cars that grain has been delivered through a tubular nozzle that is curved to point at right angles, or thereabout, to the main spout, and is capable of being revolved thereon, so as to shoot the grain in any direction at right angles thereto. Such a construction does not answer my present purpose, for the nozzle, being tubular or closed, would be liable to clog with lumps of coal or like material. Moreover, the form of the nozzle is such as renders it impracticable as regards strength to withstand the impact of heavy material. I therefore disclaim the construction referred to; but

What I claim as new, and desire to secure by Letters Patent, is—

1. An open shunting-apron that is capable of being reversed or swung around in a hori-

zontal plane, for the purpose of deflecting the descending current of material to either side of the chute, substantially as specified.

2. The combination, with the delivery end 5 of a coal-chute, of a shunting-apron attached thereto by a sliding hinge in such a manner that it may be reversed in a horizontal plane and securely locked in position, for the pur-

pose of deflecting the material to either side of the chute, substantially as described.

In testimony whereof I affix my signature in presence of two witnesses.

ABIATHER CHADWICK.
